FUEL CONTROL FOR COMBUSTION APPARATUS

John W. Miller and Raymond E. Fell, Lansing,
Mich., assignors to Motor Wheel Corporation,
Lansing, Mich., a corporation of Michigan

Application February 3, 1941, Serial No. 377,116

8 Claims. (Cl. 158—91)

This invention relates to combustion apparatus employing liquid fuel burners capable of operation with a variable fuel supply to produce a variable heat output, and more particularly to the mechanism for controlling the supply of fuel to such burners.

Vaporizing pot type burners which are employed in combustion apparatus of the type to which this invention relates are capable of a wide variation in heat output. The output of the burners is primarily governed by the quantity of fuel supplied thereto, and may be controlled by varying the rate of delivery of fuel to the burner.

For maximum efficiency of operation the air needed for combustion of the fuel must be supplied to the burner in the proper quantities to completely consume the fuel. Provision for control of the air supply usually has been provided in the form of an automatic draft regulator located in the flue outlet from the combustion chamber of the apparatus, although other forms of control devices have been employed. Such control devices can be adjusted to vary the draft on the burner, and consequently the supply of air, in accordance with requirements for best efficiency. Once adjusted, the draft is maintained practically constant.

Thus, in order to obtain maximum efficiency, it is necessary to adjust the draft regulator every time the fuel flow is changed and to adjust the fuel control every time the draft is changed. It is difficult for an operator to coordinate the two controls by manual adjustment of each unless they have been calibrated so as to indicate when they are properly coordinated. Even then, some operators will not take the trouble to adjust the other control every time one of them is changed.

Accordingly, the principal object of the present invention is to provide mechanism for automatically coordinating the fuel and air supplied to a burner whereby maximum efficiency at all stages of operation of the burner is obtained.

Another object of the invention is to provide means whereby the heat output of the burner can be regulated merely by controlling the draft thereon.

Still another object is to provide means whereby in combustion apparatus having draft regulating mechanism, the supply of fuel to the burner is automatically varied in accordance with changes in the draft produced by said regulating mechanism.

Briefly, the invention comprises mechanism as-

associated with the combustion apparatus in such a way that it is operated by changes in draft, and is coupled to the fuel regulating system whereby an increase in the draft causes a corresponding increase in the fuel supply, or a decrease in draft causes a corresponding decrease in the fuel supply.

The foregoing objects, and others more or less ancillary thereto, will more fully appear in the following specification, when read in connection with the accompanying drawings, wherein:

Figure 1 is a fragmentary elevational view of a circulating heater embodying the invention;

Figure 2 is a cross-sectional view of the apparatus shown in Figure 1 taken on the line 2—2 of Figure 1;

Figure 3 is a fragmentary elevational view, with parts broken away, of a modified form of the invention; and

Figure 4 is a cross-sectional view taken on substantially the line 4—4 of Figure 3.

The combustion apparatus disclosed in Figure 1 comprises a circulating heater having an outer casing 10 and an inner shell 11. The latter is divided into a combustion chamber 12 and an air jacket 13 by an annular shoulder 14. A vaporizing pot type burner 15 is located within the air jacket and held in tight engagement with the shoulder 14 by a bottom wall 16 in telescopic engagement with the lower end of the shell 11. The bottom wall 16 has a large central opening 17 therein to permit the entry of air to the air jacket 13. The bottom wall 16 is in telescopic engagement with the lower end of outer casing 10 also, and is provided with openings 18 to permit the circulation of air between the casing 10 and shell 11.

The burner 15 is preferably of the type disclosed in Valjean Patent No. 2,186,156, granted January 9, 1940, wherein its operation is described. The burner is provided with primary air inlet openings 19 above and below a central partition 20, and with secondary air inlet openings 19a above the top wall 21.

The burner 15 is supplied with fuel from a suitable source, such as a supply tank (not shown), through a pipe 24. The pipe 24 is connected to a fuel control 25 which is provided with a metering valve 26 operating vertically relative to a valve seat 27. The valve is normally urged vertically upward by a coil spring 28. Leading from the valve seat 27, and connecting the fuel control 25 to the burner, is a pipe 29 through which fuel is admitted to the burner. The fuel control 25, here shown, is of the

constant level type, wherein a supply of oil is maintained at a level above the pipe connection 29a so that oil will flow to the burner.

The flow of fuel to the burner is regulated by vertical movement of the valve 26, upward movement opening the valve and downward movement closing it.

Combustion chamber 12 communicates with a chimney 22 through a flue outlet 23. In a side wall of the flue outlet 23 is an automatic draft regulator, preferably of the type shown in Miller Patent No. 2,194,608 granted May 26, 1940. The draft regulator comprises a pivoted blade 30 having a knob 31 thereon to which a weight is attached and by means of which the air pressure required to open the regulator is varied. The draft on the burner can be varied by rotating the knob 31 to admit more or less air to the flue outlet through the draft regulator. The draft regulator, when once set, maintains a substantially constant draft on the burner.

Heretofore it has been necessary in apparatus of the type just described, when increasing or decreasing the output of the heater, to adjust separately both the fuel control and the draft regulator. The improvement which this invention constitutes consists of means, which in a manner of speaking couples the draft to the fuel control, whereby regulation of the draft also adjusts the fuel control.

The apparatus shown in Figures 1 and 2 comprises a sheet metal housing 32 having parallel side walls 33, and an arcuate bottom wall 34. It also has an upright front wall 35 and a top wall 36 having an opening 37 therein. Preferably all of the walls mentioned are tightly sealed together whereby the only means for admission of air to the housing is through opening 37.

Pivotedly mounted within the housing on a shaft 38 is a vane 39. The vane fits the side and bottom walls 33 and 34 respectively as snugly as possible, while still permitting the vane to pivot about its axis 38. The vane divides the housing into a high pressure section 45 and a low pressure section 46. A counterweight 40 is connected to the vane 39 to substantially balance it.

The housing 32 is connected to the flue outlet 23 and communicates therewith through a duct 41 opening into the flue outlet.

On one end of the shaft 38 outside of the housing is a crank arm 42 to which a long rod 43 is pivotally attached. The lower end of the rod is pivoted to one end of a lever 44 which in turn is pivoted to the top of the fuel control 25 for rotation in a vertical plane. The lever 44 is located so that it rests on the upper end of valve 26 and by its weight tends to force the valve to closed position.

In the operation of the device just described, some oil is admitted to the burner by lifting the rod 43 manually for a short interval. The burner is then lighted, and the ensuing heated air passing up the chimney 22 creates a draft on the burner. This draft, or pressure difference, between the interior and exterior of the burner operates on the vane 39 tending to swing it counter-clockwise (as viewed in Figure 2). This raises lever 44 which permits the spring 28 to open valve 26 and admit fuel to the burner. It will be obvious that any given draft will swing the vane 39 just so far and open the valve 26 a corresponding amount, which it will maintain as long as the draft is constant.

If a greater flow of fuel, and a consequent

increase in heat from the heater is desired, the knob 31 is rotated to increase the draft on the burner. The increased draft will swing the vane 39 still farther, thus lifting the lever 44 to a higher position and admitting more fuel to the burner. Conversely, a decrease in the draft occasioned by movement of knob 31 will diminish the flow of fuel.

For proper results, the size and weight of the vane 39, the weights of the counterbalance 40, crank arm 42, rod 43 and lever 44, as well as the stiffness of spring 28, must be properly chosen so that the entire device is in proper balance at zero draft.

15 The modified form of the invention shown in Figures 3 and 4 is used in connection with combustion apparatus identical with that previously described. Only a part of the heater is shown. It comprises an outer casing 10', an inner shell 11', a bottom wall 16' and a burner 15'. The inner shell is connected to a chimney by a flue outlet having an automatic draft regulator, such as draft regulator 30 described above.

20 Fuel is supplied to the burner 15' through pipes 25 24' and 29' and a fuel control 25'. Within the fuel control is a valve 26' having a spring 28' surrounding it and tending to open the valve.

25 Mounted on top of the fuel control 25' by means of a bracket 50 is a draft actuated fuel control 30 regulating device. It comprises a sheet metal housing 51 composed of two relatively large dish shaped halves 52 and 53. The halves 52 and 53 are provided with radial peripheral flanges 54 and 55. Within the housing 51 is a large and exceedingly flexible diaphragm 56. The periphery of the diaphragm is located between the flanges 54 and 55 and the latter are bolted or otherwise secured together. The diaphragm 56 and the half 53 together form a low pressure section of the housing 51. The diaphragm 56 and half 52 provide a high pressure section of the housing. The diaphragm has a very small aperture 56a therein to permit bleeding of air from the high pressure section to the low pressure section. Secured to the diaphragm is a reenforcing sheet 57.

30 An adjusting screw 58 is threaded into a bushing 59 in the center of half 53 of the housing 51 and extends into the housing. A spring retainer 60 is mounted on the inner end of the adjusting screw 58 and a very light spring 61 is interposed between the spring retainer and the diaphragm.

35 Secured to the center of the diaphragm 56 is a rod 62 which extends through a hole in the half 52 of the housing and the bracket 50. The outer end of the rod 62 passes through a hole in an L shaped lever 63. A pair of adjusting buttons 64 are threaded or frictionally secured to the rod 62 on opposite sides of the lever 63.

40 The lever 63 is pivoted at 65 to the top of the fuel control and rests on the upper end of the valve 26'.

45 The half 53 forming the low pressure section 50 of the housing is connected by a pipe 66 and suitable couplings to the fuel feed pipe 29', and is therefore in open communication with the burner. Of course, the low pressure section may, if desired, be connected by pipe 66, or its equivalent, to any other part of the apparatus, so long as the low pressure side is under the influence of the low pressure within the combustion apparatus. Half 52, the high pressure section of the housing, is open to the atmosphere through the 55 hole through which the rod 62 extends and

through a special opening 67 provided for that purpose in section 52.

The operation of the burner 15' is the same as that of burner 15. The draft on the burner is regulated by a draft regulator, such as that described in connection with the form of the invention shown in Figures 1 and 2.

When a draft has been created, it takes over control of the fuel supply to the burner. The air pressure within half 53 of the housing 51 will be substantially that within the burner, while the pressure in half 52 will be atmospheric pressure. The diaphragm will move toward the left (in Figure 4) against the action of spring 61, thereby pulling on rod 62 and lifting lever 63. This will permit the valve 26' to open. The position of the diaphragm will change every time the draft changes, either permitting valve 26' to open, or closing it.

Since the draft, or pressure difference, between the inside and outside of the apparatus is not very great, the diaphragm must be quite large and very flexible. It may be made of vellum or like material.

Initial adjustment of the draft to the oil flow may be made by moving the buttons 64 on the rod 62, as well as by changing the compression of spring 61 by the screws 58. By manual manipulation of one or the other of these parts, sufficient oil can be admitted to the burner to initiate combustion. As soon as combustion gets under way, the draft regulator takes over control of the flow of fuel.

In the form of the invention shown in Figures 3 and 4, the part of the fuel pipe 29'a leading horizontally into the burner is rarely completely filled with fuel. It is filled only when for some reason the burner becomes flooded. Thus, under ordinary circumstances the draft within the burner is communicated to the diaphragm. If the burner does become flooded so that the pipe 29'a is filled with fuel, then the draft no longer operates on the diaphragm and the valve 26' is permitted to close, shutting off the fuel flow until sufficient fuel in the burner is consumed to open pipe 29'a and permit the draft in the burner to act on diaphragm 56. The aperture 56a in the diaphragm permits air to leak from the high pressure section to the low pressure section so that the diaphragm may return to its normal position. This feature of the invention is an important safety factor. Without it, diaphragm 56 would become locked, so to speak, in the position it occupied at the time fuel pipe 29'a became filled with fuel.

The reason that the draft is not communicated to the diaphragm when the pipe 29'a is filled with fuel is that the difference between the atmospheric pressure on one side of the diaphragm and the sub-atmospheric pressure in the burner is not great enough to push the liquid in the pipe 29'a out of the way. Burners of this type operate normally under a draft of around .08 inch of water, while the maximum draft is about .12 inch of water.

From the foregoing it will be seen that this invention provides a means for automatically coordinating the flow of fuel to the burner and the air required to consume it. It therefore eliminates errors usually occurring in the manual setting of two separate control means. Furthermore, it minimizes the number of controls that must be operated to regulate the output of the burner.

The scope of the invention is indicated in the appended claims.

I claim:

1. Combustion apparatus comprising a liquid fuel burner, a combustion chamber thereabove, a flue outlet from the combustion chamber, an adjustable automatic draft regulator associated with said flue outlet for controlling the draft on the burner, means including an adjustable metering valve for supplying fuel to the burner in regulatable quantities, and mechanism connected to the metering valve and actuated by the draft on the burner for adjusting the metering valve to vary the rate of supply of fuel to the burner in response to variations in the draft on the latter, said means including a housing, a vane pivotally mounted in said housing and dividing the latter into a high pressure section and a low pressure section, said high pressure section being open to the atmosphere and said low pressure section communicating solely with said flue outlet, and mechanism connecting said pivoted vane to said metering valve whereby pivotal movement of said vane adjusts said metering valve.

2. Combustion apparatus including a liquid fuel burner, means including an adjustable metering valve connected to the burner for supplying fuel thereto in regulatable quantities, adjustable means associated with the burner for controlling the draft thereon, a housing, a flexible diaphragm within said housing dividing the latter into a high pressure section and a low pressure section, said high pressure section being in open communication with the atmosphere and said low pressure section communicating solely with said burner, and mechanism connecting said diaphragm to said metering valve whereby to adjust the latter to control the rate of supply of fuel to the burner in response to variations in the draft thereon.

3. Combustion apparatus comprising a liquid fuel burner, a combustion chamber communicating therewith and having a flue outlet, means for varying the draft on the burner including an adjustable draft regulator associated with the flue outlet, means including an adjustable metering valve connected to the burner for supplying fuel thereto in regulatable quantities, and mechanism for adjusting the metering valve to vary the supply of fuel to the burner in accordance with variations in the draft on the burner, said mechanism comprising a housing, means dividing said housing into a high pressure section open to the atmosphere and a low pressure section communicating with the interior of the combustion chamber, said dividing means being connected to said metering valve and movable under the influence of variations in the pressure difference between the high and low pressure sections of the housing to adjust said valve.

4. Combustion apparatus as defined in claim 3 wherein said dividing means comprises a diaphragm having a small opening therein providing restricted communication between said sections.

5. Combustion apparatus as defined in claim 3 wherein said housing is connected to said flue outlet.

6. Combustion apparatus comprising a liquid fuel burner, a combustion chamber communicating therewith and having a flue outlet, means for varying the draft on the burner including an adjustable draft regulator associated with the flue outlet, means for supplying fuel to the burner in regulatable quantities including an

adjustable metering valve and a conduit connecting said valve to the burner above the normal level of fuel therein, and mechanism for adjusting the metering valve to vary the supply of fuel to the burner in accordance with variations in the draft on the burner, said mechanism comprising a housing, means dividing the housing into a high pressure section open to the atmosphere and a low pressure section, a conduit connecting said low pressure section with said first mentioned conduit and thereby communicating with the interior of the burner, said dividing means being connected to the metering valve and movable under the influence of variations in the pressure difference between the high and low pressure sections of the housing.

7. In combination, combustion apparatus including a liquid fuel burner and a combustion chamber having a flue outlet connected together to provide an apparatus having a pressure differential between its interior and its exterior during operation of the burner, means including an

adjustable metering valve connected to the burner for supplying fuel thereto in regulatable quantities, and pressure responsive means located exteriorly of the apparatus and communicating with the interior of the apparatus including a member adapted to be moved by changes in the pressure differential between the interior and exterior of the apparatus, said movable member being connected to said fuel metering valve for adjusting the latter to respectively increase or decrease the supply of fuel to the burner in accordance with increases or decreases in pressure differential between the interior and exterior of the apparatus.

8. The combination defined in claim 7 which also includes adjustable means associated with the apparatus for varying the pressure difference between the interior and exterior of the apparatus.
